UNITED STATES PATENT OFFICE.

CHARLES F. BURKHART, OF NEW YORK, N. Y., ASSIGNOR TO BURKHART CORPORATION, OF BUFFALO, NEW YORK, A CORPORATION OF NEW YORK.

GUARD-OPERATING MECHANISM FOR SHOE-DRESSING MACHINES.

1,278,848.

Specification of Letters Patent. Patented Sept. 17, 1918.

Application filed February 3, 1914. Serial No. 816,273.

To all whom it may concern:

Be it known that I, CHARLES F. BURKHART, a citizen of the United States, residing at New York, in the county of New York and 5 State of New York, have invented certain new and useful Improvements in Guard-Operating Mechanism for Shoe-Dressing Machines; and I do hereby declare the following to be a full, clear, and exact description of the invention, such as will enable others skilled in the art to which it appertains to make and use the same.

This invention relates to guards and guard operating mechanisms for shoe polishing 15 machines and has for an object to provide guards for positioning the shoe upon a shoe polishing machine and a guard for preventing the application of dressing to undesirable parts of the shoe with improved means 20 for simultaneously operating the said guards.

A further object of the invention is to provide a guard which engages the rear of a shoe, a guard which engages the instep of a shoe both for positioning and holding the 25 shoe in such position, and a third guard for also engaging the instep and sides of a shoe to prevent the application of dressing thereto with means for actuating said guards in synchronism.

With these and other objects in view the invention comprises certain novel constructions, combinations and arrangement of parts as will be hereinafter more fully described and claimed.

Figure 1 is a perspective view of the front and rear guard and their operating mechanism removed from the housing and supporting devices.

Fig. 2 is a view of the guard operating 40 mechanism in side elevation, the housing being broken away to show the device.

Fig. 3 is a view similar to Fig. 2, the parts being moved to engaging position.

Fig. 4 is a perspective view of the instep 45 guards and the means for operating.

Fig. 5 is a detail fragmentary view of the initial releasing means.

Fig. 6 is a view of the cloth polisher mechanism in associated position, but removed from any casing or supporting means.

Fig. 7 is a sectional view taken on line 5-5 of Fig. 6.

Fig. 8 is a sectional view of one of the air

cushions for cushioning the reciprocation of the polisher head.

Fig. 9 is a view of the polisher head shown in side elevation.

Fig. 10 is a detailed sectional view showing the cam and rack for raising and lowering the polisher head.

Like characters of reference designate corresponding parts throughout the several views.

The present invention embodies a guard 10 adapted to engage the rear of the shoe, a guard 11 adapted to engage over the instep of the shoe both for positioning and holding the shoe upon the foot rest 12 as indicated particularly at Fig. 2, and a third guard 13 also engaging over the instep and carrying therewith an apron 14 to prevent the application of the dressing to the upper. The present invention includes the said clamps 10, 11 and 13 and the means for simultaneously operating the said clamps to bring them into initial clamping engagement with the shoe and to release them from such clamping engagement when the work of the machine has been accomplished.

The clamps are intended to be operated 80 with a polishing machine provided with a carriage shown conventionally at 15, such carriage forming no part of the present invention except as it co-operates with the guard operating device and no operating 85 means for the carriage is shown, it being understood that the carriage is reciprocated as indicated at Figs. 2 and 3 by any approved or convenient mechanism.

The clamp 10 is carried upon rods 16 90 which slide through guides 17 and is actuated by a weight 18 attached to a cable 19 passing over a pulley 20 and connected with a lever 21. It will be obvious, especially from Fig. 1 that the tendency of the weight 18 is to move the rods 16 and the clamping member 10 in the direction indicated by the arrow in Fig. 1 or toward the shoe as indicated in dotted lines in Fig. 2. It is obvious, therefore, that when the weight 18 is permitted to act the clamp 10 will be moved into clamping position. The clamp 11 is carried upon a yoke 22 pivoted to swing upon trunnions 23 so that it may move in the direction indicated by the arrow in Figs. 1 and 2 toward the shoe rest 100 105

12 as indicated at Fig. 3 to clamp the shoe mounted upon such shoe rest. The movement of the yoke 22 and clamp 11 toward the shoe is accomplished to a certain extent by the weight of the yoke and clamp itself but also by the weight 24 which is connected with a cable 25 passing over a pulley 26 and to a bell crank lever 27 pivoted to an arm lever 28 which is in turn pivoted at 29 to a bracket 30 secured to any convenient part of the housing as indicated in full lines at Fig. 5 and dotted lines in Figs. 2 and 3. The connection between the lever 27 and the yoke 23 consists of a link 31 and crank-arm 32, the latter being rigidly mounted upon one of the pintles 23. It is obvious, therefore, that as the lever 27 is actuated by the weight 24 the clamp 11 will move downwardly from the position shown at Fig. 2 to the position shown at Fig. 3 and thereby clampingly engage the shoe. The clamps 10 and 11 are connected to move in synchronism by means of a link 33, the said link being provided with a slot 34 where it engages with the lever 27 to permit a slight variation of the registration of the clamps 10 and 11 to conform to different sizes and shapes of shoes. It is obvious that the guards 10 and 11 will, however, move simultaneously into clamping position actuated by the weights 18 and 24 and that such guards will by reason of such independent weights engage the shoe with independent clamping force, variation being permitted by the slot as aforesaid.

Above the yoke 22 the apron 14 is mounted to slide in guide-ways 35 rigidly secured to the housing and also to slide upon a rod 36 rigidly secured to the housing in any approved manner as by having its opposite ends carried by angle-irons 37. The apron also carries a shaft 38 upon which are mounted rollers 39 bearing upon cam surfaces 40 of the yoke 22 and also provided with a roller 41 engaging upon the cam 42 also carried by such yoke. A spring 43 or other means is provided for assisting in the movement of the apron downwardly the raising being accomplished by the cams 40 and 42 bearing under the rollers 39 and 41. It is obvious, therefore, that as the mechanism moves to raise the guard 11 and move the guard 10 backwardly the apron 14 and guard 13 are also raised.

In its initial position the mechanism is such as to hold the guards away from the shoe, such position being maintained by means of a cam 44 carried by the carriage and supporting the bell-crank lever 27 through the medium of a roller 45 and through the medium of a link 46 engaging over a pin 47 carried upon a lever 48 held in position shown at Fig. 1 normally by the yoke 49 carrying the cloth polishing apparatus which forms the subject matter

of a co-pending application, Serial No. 816,272, filed on even date herewith. With the cloth polisher raised as shown at Figs. 1 and 2 the lever 27 is held forwardly and the guards therefore held as at Fig. 1 out of engaging position. When the carriage 15 starts forward as indicated by the arrow in Fig. 2 upon the starting of the machine the roller 45 rides down the incline of the cam 44 and thus permits the lever 27 to move to the position shown at Fig. 3 which permits the weights 18 and 24 to move the guards into engaging position and also permits the spring 43 to act likewise. It is desirable that the clamping members remain in clamping position during several reciprocations of the carriage as the carriage reciprocates several times to finish the brushing and applying function and also to retain the shoe in position while the cloth polisher is operating. For this purpose as the carriage moves forward to the position shown at Fig. 3 the cam 44 lifts the link 46 until it is released from the pin 47 as shown at said Fig. 3 so that when the carriage returns to the position shown at Fig. 2 the link being released from and riding upon the pin 47 permits the bell-crank lever 28 to ride up the incline of the cam 44 without affecting the position of the upper end of the lever 27. After the polishing and applying functions have been performed by the several reciprocations of the carriage it is intended that the carriage shall stop and remain stationary while the cloth polisher is brought into action. The carriage remains stationary at the position shown at Fig. 2 with the bell-crank lever supported upon the cam 44. When the cloth polisher is lowered into position by lowering the yoke 49 the spring 50 throws the lever 48 forward until the link 46 again engages over the pin 47 and as the cloth polisher rises to inoperative position as shown at Fig. 2 the lever is thrown backwardly thus drawing the lever 27 back to the position shown at Fig. 2 which releases the shoe by moving the guards to the position shown at Fig. 2.

The yoke 49 is pivoted at 51 and is raised by means of the sprocket chains 52 passing over the sprockets 53, which said sprockets 53 are carried upon the shaft 54. The shaft 54 is provided with a pinion 55 engaged by a rack 56 which in turn is actuated by an eccentric 57. The eccentric 57 is carried by a gear 58 driven from the motor 59.

The yoke 49 is lowered by its own weight when the sprockets 53 are rotated in one direction and carries the shoe cleaning and polishing heads 60 which are oscillated by the links 61 driven from the crank 62 which in turn is driven by the worm 63 and sprocket chains 64 from the motor 59.

The cleaning heads 60 are mounted upon

shafts 65 which are provided with segmental teeth as shown at Fig. 10 engaging the racked side of the piston 66 mounted in the closed cylinder 67 to cushion the oscillation 5 of the cleaning heads.

It will thus be seen that the shoe is engaged upon the initial movement of the carriage to start the operation and is retained in such position by the weights until the 10 entire operation of brushing, applying and polishing have been accomplished when the guards are automatically moved away to release the shoe. It will also be noted that the guards are all actuated by weights or springs 15 which only yieldingly engage the shoe thus permitting the shoe to be withdrawn at any time should the party being operated upon desire to so remove the shoe.

I claim:

- 20 1. In a shoe polishing machine embodying a reciprocable carriage and a cloth polisher acting after the completion of reciprocation of the carriage, guards positioned to engage a shoe at the rear, at the front and at the 25 top; mechanism actuated from the initial movement of the carriage to bring the guards simultaneously into clamping position; and means actuated from the final movement of the cloth polisher to remove the guards from engagement.
2. In a shoe polishing machine embodying a reciprocating carriage and a cloth polisher acting after the completion of reciprocation of the carriage, clamps for engaging a shoe; means actuated from the initial movement of the carriage for bringing the clamps into engaging positions; and means actuated from the final movement of the cloth polishing mechanism for moving 35 said clamps out of engaging position.
3. In a shoe polishing machine embodying

a movable carriage and a movable cloth polishing mechanism acting after the completion of a cycle of movement of the carriage, means to engage a shoe; mechanism to bring the engaging means into engagement at the initial movement of the carriage; and means to remove the engaging means from engagement at the final movement of the cloth polisher. 45

4. In a shoe polishing machine, a shoe cleaning member, an actuating mechanism adapted to actuate the shoe cleaning member, a shoe clamping member and means to operate the shoe clamping member from the 50 actuating mechanism.

5. In a shoe polishing machine, a shoe clamp, clamp operating mechanism, a carriage and means carried by the carriage for controlling the clamp operating mechanism. 60

6. In a shoe polishing machine, a shoe clamp, a clamp operating mechanism, a carriage, means carried by the carriage for controlling the clamp operating mechanism, actuating mechanism, means actuated by the 65 actuating mechanism in conjunction with the carriage at a predetermined position in its cycle of movement to actuate the clamp operating mechanism.

7. In a shoe polishing machine, a carriage, a shoe clamp, shoe clamp actuating mechanism actuated at each reciprocation of the carriage without actuating the clamp and means including the clamp actuating mechanism for actuating the clamp following a 70 certain reciprocation of the carriage.

In testimony whereof I affix my signature in presence of two witnesses.

CHARLES F. BURKHART.
